UNITED STATES PATENT OFFICE

LE ROY WILCOX, OF DETROIT, MICHIGAN, ASSIGNOR TO COPE-SWIFT COMPANY, INC., A CORPORATION OF MICHIGAN

OIL BURNER

Application filed November 18, 1927. Serial No. 234,075.

This invention relates to oil burners such as are used in connection with furnaces and the like for heating residences or other buildings or for other purposes, the principal object being to provide a new and novel construction for the same, efficient in operation and economical to manufacture.

Another object is to provide an oil burning mechanism in which oil is fed into a rotating cup-shaped receptacle which delivers the oil to the air stream in a finely divided state which allows it to be readily gasified.

Another object is to provide an oil burning mechanism comprising an open ended casting in which a cup-shaped receptacle is positioned in spaced relationship with respect to the walls thereof, the receptacle being secured to a rotating shaft to which a fan is secured for driving air past the receptacle, a member including a notched nozzle being provided for delivering oil to the interior of the receptacle, and the side walls of the receptacle being tapered outwardly from the bottom of the same whereby the rotation of the receptacle throws the oil off from the edges thereof in a finely divided state into the stream of air passing the same.

Another object is to provide an oil burning mechanism including a motor, a fan and an oil spraying mechanism together with suitable valves and other control mechanism mounted on a single support, whereby all of the mechanism with the support may be attached to or removed from a furnace as a unit.

Another object is to provide an oil burning apparatus including a motor, a fan and oil spraying mechanism secured together in a unitary structure which may be applied to and removed from its supporting means as a unit.

Another object is to provide a new and novel type of an automatic oil shut-off valve and operating mechanism for oil burners.

Another object is to provide a shut-off mechanism for oil burning mechanism that is thermostatically controlled by the pilot light.

Another object is to provide a pilot light including a passage increasing in internal

area from the point of entrance of the gas to the same to the discharged end of the same.

A further object is to provide a pilot light construction that will withstand detonations and blasts of air in the fire pot without being extinguished thereby.

The above being among the objects of the present invention the same consists in certain features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Fig. 1 is a front view of a furnace showing the application of my oil burner mechanism thereto.

Fig. 2 is a perspective view of the supporting plate, burner casing, oil trip valve and pilot light assembly.

Fig. 3 is a perspective view of the motor, fan and oil cup in assembled position.

Fig. 4 is a vertical sectional view taken axially through the center of the complete assembled apparatus.

Fig. 5 is a side view of the oil trip valve and thermostatic operating means for the same.

Fig. 6 is a broken top view of the pilot light member.

Fig. 7 is a view from the back of the device showing the arrangement of the valves in the oil line.

The conventional type of oil burner employed in connection with furnaces and the like for heating buildings invariably includes a multiplicity of parts so supported and arranged relative to each other as to form a bulky and ponderous assembly requiring much space and involving considerable work in the applying and removal of the same to and from a furnace. Such constructions, while unitary in one sense of the word, usually depend upon a supporting frame including standards of various sizes and shapes to which the various parts are se-

cured, in addition to the usual plate which is necessary to close the opening in the furnace through which parts of the burning mechanism must project.

5 By the use of the present invention I am enabled to provide a burning mechanism of unitary construction wherein the door or plate which is employed for closing the opening into the furnace is used as a support for 10 the entire burner mechanism which, because of its construction, is extremely compact and which may be applied to or removed from a furnace within a period of a very few minutes, thus making it readily serviceable without any substantial delay in the operation of the furnace.

In the accompanying drawings I show, by way of illustration, a furnace having sides 10, dome 11 and front 12. The front 12 is 20 provided with the usual openings closed by the doors 13 and 14 and is provided with a lower opening 15 which is closed by the plate member 16, secured in position by screws or other suitable means 17. The plate 16 is open 25 at its center as indicated in Fig. 4, and extending inwardly therefrom in inwardly converging relationship is the casing 18 which may be integrally formed with the plate 16. A second circular casing 19 is secured to 30 the rear end of the casing 18 by bolts such as 20 and nuts 21 which pass through the flanges 22 and 23 which are formed on the casing 18 and 19 respectively. Closing the rear face of the open center of the plate 35 16 is a plate 24 provided with a relatively large central opening 25, it being held in place by being clamped between the flange 26 of the motor supporting frame 27 and the plate 16. The motor supporting frame 27 40 which is shown in section in Fig. 4 extends rearwardly from the plate 24 and is located on the plate 16 by means of the dowels 28 and screws 29 of which there are only two each. The supporting frame 27 is provided 45 with a plurality of openings 30 around its circumference for the entrance of air to the interior of the same. Removably secured within the rear end of the supporting frame 27 by means of set screws 31 is an electric 50 motor comprising a casing 32, armature 33, armature shaft 34 and bearings 35 and 36, the casing 32 extending into the frame 27 to a point adjacent the rear edges of the openings 30 so as not to restrict the flow of air 55 through the same. To the inner end of the armature shaft is secured an extension 37 by means of a screw 38, the extension 37 terminating in a flange 39 between which and the sleeve 40 a fan of the axial displacement 60 type 41 is clamped. A cup shaped member 42 is secured to the inner end of the sleeve 40 by means of the screws 43 which project through the bottom of the cup, the flanges 65 of the sleeve 40, the fan 41, and are threadably received in the flange 39 of the extension

37, thus serving to secure all of these parts in assembled relationship. The armature shaft and extension are hollow and extending through the same from the back end of the motor, and rotatable relative thereto is an oil delivery tube 44 which terminates at its inner end short of the bottom of the cup 42. A sleeve like nozzle member 45 having an opening in its otherwise closed end for the passage of the tube 44 is secured within the sleeve 40 and extends from the inner end of the extension 37 to a point inwardly spaced from the bottom of the cup 42. Suitable packing 47 is secured in the nozzle 45 around the tube 44 by means of a nut 48 in order to prevent leakage of oil from the interior of the nozzle 45 back around the outside of the tube 44 to the motor. The inner edge of the nozzle 45 is provided with a plurality of radial notches or slots 50 for a purpose to be described later.

70 A flexible strip 51 provided with openings 52, spaced in accordance with the spacing of the openings 30 in the frame 27, is provided around the circumference of the frame 27 in over-lapping relationship with respect to the openings 30 so that by moving the strip 51 circumferentially of the casing 27 the effective area of the openings 30 may be varied 75 in order to control the flow of air to the burner.

75 The outer end of the tube 44 which projects out past the rear end of the casing 32 is provided with a connection 53 which serves to connect it to the shut-off valve 54. The shut-off valve 54 is connected by a line of piping 55 including a union 56 to an oil trip valve the body of which is designated as 56 and which in turn is connected by the pipe 57 to the solenoid valve which is thermostatically controlled by the temperature of 80 the room or space being heated, in the conventional manner. The valve 58 is connected by the pipe 59 to a strainer 60 which in turn is connected by a line of piping 61 to a suitable source of oil under a suitable pressure. Oil enters the apparatus through the line of piping 61, strainer 60, pipe 59, passes 85 through the valve 58 and then through the piping 57, trip valve 56 and piping 55 to the valve 54 from which it is led into the tube 44 and discharged into the interior of the nozzle 45. As the armature shaft 34 of the motor rotates, the extension 37, fan 41, nozzle 45 and cup 42 are caused to rotate therewith. When the fan 41 is thus rotated, air 90 is drawn into the interior of the frame 27 through the openings 52 and 30 and forced inwardly through the casings 18 and 19 around the exterior of the cup 42 to the fire pot. At the same time the oil being discharged into the nozzle 45 is carried to the walls of the interior opening thereof by centrifugal force and when it reaches the notches 50 at the inner end thereof it is 95 thrown outwardly by the centrifugal forces 100

105

110

115

120

125

130

135

140

acting upon it into the cup 42. The oil being discharged through the notches 50 is broken up into a plurality of finely divided particles. The oil thus discharged into the cup 42 is 5 carried out against the side walls thereof by the centrifugal force acting upon the same. Due to the outwardly diverging relationship of the side walls of the cup 42, the oil is slowly carried out to the open end of the 10 cup in the form of a thin film, gradually decreasing in thickness to the end of the cup, at which point it is thrown by centrifugal force outwardly into the air stream flowing around the cup, in the form of a fine mist, 15 it being picked up by the air stream and commingling therewith is carried into the fire pot where it is ignited and burned. Due to the fact that the casings 18 and 19 are positioned within the fire pot, a certain amount of 20 heat is transmitted through the walls thereof and heats the cup 42, and this heat serves to vaporize and gasify a large percentage, and at times all of the oil within the cup 42 by 25 the time it is discharged from the open end thereof. Inasmuch as the air for combustion is passed around the outside of the cup 42 which is cooled thereby, such heat transfer does not affect the cup 42 sufficiently to raise its temperature to a point where the oil 30 within the cup 42 will coke and thus build up undesirable deposits in the cup 42. Further, because of the fineness of the particles of oil discharged at the open end of the cup 42 into the air stream, I am enabled to use 35 the axial displacement type of fan 41 shown with the relatively lesser velocity of air in this construction than is possible in the conventional construction now on the market, and this feature serves to provide an almost 40 noiseless operating device.

In connection with my burner I provide a pilot light of novel construction comprising a hollow tube-like casing or member 62 provided with a flange 63 which is secured by the 45 screws 64 to the front plate 16. A valve 65 connected in the gas line is provided with a small tube or discharge pipe 66 for discharging gas into the interior of the member 62. The member 62 extends from the 50 plate 16 to a point below the end and preferably rearwardly of the inner open end of the casing 19 where it terminates in an upwardly extending opening 67. The internal cross sectional area of the member 62 gradually 55 increases from the flange 63 to the opening 67. I find that with this construction when the flame of the pilot light is burning in normal condition above the opening 67, and a sudden blast of air or other increase in pressure 60 in the fire pot occurs, the flame instead of becoming extinguished as so often occurs in conventional constructions, merely retreats into the member 62 and moves back towards the plate 16 within the interior thereof without becoming extinguished. Upon drop in 65 pressure in the fire pot to normal conditions the flame again moves out to its normal position above the opening 67. The taper formation of the interior walls of the member 62 permits such receding of the pilot light 70 flame into the member 62 without extinguishing it, and this feature is extremely valuable from a safety standpoint as will be readily recognized.

In case, however, that the pilot light 75 should become extinguished from some unforeseen reason, and to prevent an explosion of the oil within the furnace which might occur as a result thereof, I provide a novel means for shutting off the flow of oil to the burner whenever the pilot light becomes extinguished. This means is as follows:—The trip valve 56 is provided with a valve member 68 which is constantly urged by spring 69 towards closed position so as to prevent the passage of oil through the valve 56. The valve member 56 is provided with a stem 70 which projects out past one end thereof. An arm 71 is pivotally mounted at 72 on the valve body 56 and to its free end a lever 73 is pivotally secured by the pin 74. A second arm 75 is pivotally mounted on the valve body 56 at 76 and is pivotally secured to the arm 73 midway between its ends by the pin 77. The relation of the arm 71 with respect to the end of the stem 70 is such that when the arm 73 is swung about the pin 74 so that the line connecting the pins 74 and 77 pass inwardly of the axis of the pin 76 with respect to the valve body 100 56, the arm 71 is drawn towards the body 56 of the valve and exerts a pressure on the stem 70 sufficient to move the valve member 68 to permit the flow of oil past the same, and at the same time the pressure of the spring 69 acting on the arm 71 through the valve 105 stem 70 tends to swing the lever 73 closer to the valve body and thus tends to retain the valve member 68 in open position. It will be noted, however, that should the free end of the arm 73 be moved away from the body 56 of the valve sufficiently to move the line connecting the pins 74 and 77 outside of the axis of the pin 76, the pressure of the spring 69 acting through the valve stem 70 on the arm 71 will then tend to swing the arm 73 further away from the body 56 and allow the valve member 68 to close so that no oil may 110 pass through the valve. I provide a mechanism for moving the arm 73 to this last mentioned position upon extinguishment of the pilot light in the following manner:—The end of the pilot light body member 63 adjacent the opening 67 is provided with a horizontally extending flange 78, and to the flange 78 I pivotally secure by means of the screw 79 a strip of thermostatic material 80 formed to provide a plurality of reversely bent turns which terminate in an attaching end 81 to which an arm member 82 is secured 115

120

125

130

by means of rivets 83 or other suitable means. The arm member 82 extends outwardly through a slot 84 in the plate 16 where it is provided with an upwardly extending end 85 terminating in the horizontally rearwardly projecting end 86 which lies in the path of movement of the horizontally extending pin 87 secured in the free end of the lever 73. The thermostatic strip 80 is positioned sufficiently near the opening 67 as to be effected by the heat of the pilot light flame burning at the same. The strip 80, upon being heated by the pilot light, operates to move the arm 82 so that it raises the end 86 thereof to a position such as is indicated by dotted lines in Fig. 5. When the end 86 is thus raised to this position the pin 87 on the free end of the lever 73 may be moved up into contact with the same in which position the pressure 20 of the spring 69 acting through the stem 70 and arm 71 acts to hold the valve member 68 in open position. Should, however, the pilot light become extinguished, the strip 80 will be cooled and will contract, tending to swing 25 the arm 82 downwardly, upon the occurrence of which the end 86 will engage the pin 87 and move the free end of the arm 63 downwardly away from the valve body 56 sufficiently to move the line connecting the pins 20 74 and 77 over the axis of the pin 76 after which the spring 69 is free to move the valve member 68 to closed position and thereby prevent further flow of oil to the furnace. When this happens, further danger of an 30 explosion within the furnace is eliminated, and notice is thereby given by the lack of heat that the apparatus has stopped functioning. The pilot light may then be again ignited which will cause the arm 82 to be moved to its upper position and the arm 73 may then be manually moved upwardly, as shown in dotted lines in Fig. 5, so as to again permit the flow of oil to the mechanism.

In order to make the above described apparatus as readily serviceable as possible, I secure an electrical plug receptacle 88 to the plate 16 and provide the electric motor 32 with a suitable conductor 89 terminating in a conventional pull plug 90 which may be connected into the receptacle 88. I also provide the solenoid valve 58 with a similar connection 91 and plug 92 which may also be readily inserted into the receptacle 88, and I provide a similar plug 93 for leading the various conductors into the receptacle 88. In this manner I am enabled to remove the assembly comprised mainly of the motor 32, frame 27, fan 41, and cup 42 with their accompanying mechanisms from the plate 16 and mechanism supported thereby by simply pulling the plugs 80 and 92 breaking the union 94 in the line of pipe 55 and removing the two bolts 29, all of which may be done in the space of a few seconds. This permits this unitary assembly to be removed and

replaced by a like assembly whenever any part of it requires attention of a service man and allows such assembly to be carried to a shop or other place of business which is properly equipped for the ready and efficient repair of the same without tying up the operation of the furnace itself for an appreciable length of time. 70

On the other hand, should the unitary assemblage of the plate 16, casings 18 and 19, pilot light, oil trip valve mechanism, or solenoid valve 58 become out of repair, the assemblage just described and as shown in Fig. 3, may be removed as described and then the last unitary assemblage described be removed 80 from the furnace by the removal of the screws 17 and the connections to the oil and gas line, and another such unit may be inserted in its place and the first mentioned unit secured thereto in the space of a very few minutes, and the last mentioned assemblage removed and repaired at leisure. Further, where it is desirable, the entire assemblage of both of the afore mentioned units may be removed as a unit from the furnace by 85 simply removing the screws 17 and breaking the oil and gas connections and pulling the plug 93, in which case a complete new assembly may be inserted in place on the furnace while the original assembly is being repaired. These features make the above described construction extremely valuable from the servicing standpoint as it permits the ready and efficient repair of the device as a 90 whole or any part thereof with a minimum of time spent at the point of use, and a minimum of time of inoperativeness of the furnace itself. 95

While I have described and shown in the drawings a specific embodiment of the present invention, it will be obvious that the same is capable of various modifications and various changes in the specific structure, and formal changes may be made in the specific embodiment of the invention described without 105 departing from the spirit or substance of the broad invention, the scope of which is commensurate with the appended claims. 110

What I claim is:

1. In combination with a furnace provided with an opening therein, a member detachably securable to said furnace for sealing said opening and provided with an inwardly extending casing, an outwardly extending frame detachably secured to said member, a 120 motor telescopically carried by said frame, and a fan and vaporizing cup carried by the shaft of said motor within said casing, said fan being of the axial displacement type and said cup being of approximately the same 125 diameter as said fan, the space between said cup and said casing providing a duct for the passage of air from said fan, said frame, motor, fan and cup being removable from said member and casing as a unit, and said cup 130

being wholly exposed upon such removal.

2. In a device of the class described, in combination, a member adapted to seal an opening in a furnace, a casing carried by said member about said opening and projecting inwardly therefrom, a frame removably secured to said member and extending outwardly therefrom, a plate removably clamped between said frame and member, said plate provided with an aperture restricting said opening, a motor supported by said frame, a shaft extension supported by the shaft of said motor and extending through said aperture, and a fan and a vaporizing cup carried by said extension inwardly of said plate and secured to said extension by common screw means, said frame, plate, motor, shaft extension, fan and cup being removable as a unit from said member and casing and wholly exposing said fan and cup upon such removal, and said fan and cup being simultaneously removable from said extension and from each other upon loosening said screw means.

3. In combination with a furnace having an opening therein, a member detachably securable to said furnace sealing the joint between itself and said furnace against the flow of air therethrough, said member being provided with an inwardly extending casing portion the inner walls of which diverge from adjacent its center, an outwardly extending frame secured to said member, a plate clamped between said frame and member provided with a central opening of substantially smaller diameter than said casing, an electric motor secured to said frame, said motor being provided with a shaft extension projecting through said opening, a vaporizing cup carried by said extension at the inner end of said casing, the walls of said cup diverging from the bottom thereof and lying in adjacent and substantially parallel relation with respect to the inner walls of said casing, an axial flow type of fan secured to said extension between said cup and plate, said frame being provided with openings therein for the entrance of air into said furnace, and an apertured band surrounding said frame for controlling the effective area of said openings.

LE ROY WILCOX.
